UNITED STATES PATENT OFFICE.

EDWARD L. KUNZ, OF BUFFALO, NEW YORK, ASSIGNOR TO ONE HAND AUTO TOP COMPANY, INC., OF BUFFALO, NEW YORK, A CORPORATION OF NEW YORK.

BALANCED TOP-FRAME.

1,334,383.

Specification of Letters Patent. Patented Mar. 23, 1920.

Application filed January 24, 1917. Serial No. 144,163.

To all whom it may concern:

Be it known that I, EDWARD L. KUNZ, a citizen of the United States, residing at Buffalo, in the county of Erie and State of New York, have invented certain new and useful Improvements in Balanced Top-Frames; and I hereby declare that the following is a full, clear, and exact description thereof, reference being had to the accompanying drawings, which form part of this specification.

Like figures on the drawings refer to like parts.

This invention relates to balanced top frames for vehicles on land or sea, particularly to that class thereof having main arms of said frames so constructed as to overcome most of the weight of the top frame during the various angular positions of said arms, from down or closed position to upright position.

One object of this invention is to provide a cross transmission device for transmitting the operating force from the operator's side to the opposite of the vehicle, without the use of the cross shaft.

Another object is to provide a practical cross transmission device in connection with the said main arms, that will simultaneously operate the two sides of the top frame, from a force applied to one side thereof.

Another object is to provide a pair of balanced arms for the top frame, which will be self-contained in their operation, starting from mountings upon the sides of the body of the vehicle, upon which they are journaled.

A further object is to provide a top frame, embodying a fanned type of lazy tongs, which shall provide spaces between the upper parts of the links of said lazy tongs, when closed, to adopt said spaces to receive the folded parts of a covering to said frame.

Another object is to provide a frame construction which shall be adjustable in parts to accommodate the same in overcoming the slack of the covering after the same has become stretched from wear.

Another object is to provide a top frame construction which shall be automatically operable separately in sections, so that one section can be closed, while the remaining section is left open.

One embodiment of my invention is here-

after described and illustrated in the drawings. The operation is explained in what I claim and set forth.

In the drawings:

Figure 1 is a side elevation of the car body showing a top frame embodying my invention attached to said body showing one section of said frame open and its adjoining section closed.

Fig. 2 is a side elevation of the top frame and body shown in Fig. 1, but in full open position.

Fig. 3 is a front elevation of the main arms shown journaled on mountings on the vehicle body.

Fig. 4 is a sectional side elevation of one of the main arms.

Fig. 5 is a sectional side elevation of an arm, being a modification of that shown in Fig. 4.

Fig. 6 shows in sectional elevation, another modification of an arm.

Fig. 7 shows a sub-shaft of one of the main arms journaled with one of the mountings.

Fig. 8 is a large detail elevation of one of the ear links showing elastic means as well as the turn-buckle, for taking up the slack in the cable cross transmission.

Fig. 9 is a fragmental plan of the top frame, showing the crossing of the cables in the transmission, inlaid in the cross rib, connecting the main arms.

Fig. 10 is an enlarged view of part of the frame, showing an adjustable feature adapted to position one of the cross ribs on said frame, for taking up the slack in the covering.

Fig. 11 is a top plan of the parts shown in Fig. 10.

Fig. 12 is a side elevation of the windshield and post attachment, showing connection with the front of the top frame.

Fig. 13 is a diagram giving an idea of the development of the link arrangement of the lazy-tongs, producing a fanning out of the upper pivotal ends of the links, to make room for the infolding of the top coverings.

Fig. 14 is an elevation of a holding bracket in which the top frame rests, when folded back.

Referring to the figures, upon the body 1, is a bracket 2 having a stub shaft 3, upon which is journaled a main arm 4. Upon the opposite side of the vehicle is a like arm, 110

similarly journaled on a stub shaft, upon the bracket on the body 1. The main arms 4, 4 are connected at their tops by a cross rib 5. Extending to the rear of each of the 5 arms 4 are lugs 6, to which are pivoted the ends of the diagonal bow 7. Connecting the body 1, with the upper part of the bow 7, and a cross rib 5, is shown the band 8, which is continued forward to connect other cross 10 ribs of the top frame.

To each of the main arms 4, is connected a lazy tong set of links, comprising the following parts: a link 9, pivoted at the point 10, to the upper part of one of the main 15 arms 4. To the link 9 is pivoted the link 11 at the point 12. The link 11 is pivoted at the point 13 to the ear link 14. The link 11 is pivoted at the point 15 to the link 16, and the link 16 pivoted to the point 17 to the link 18, 20 and the link 18 is pivoted to the point 17 to the link 18, and the link 18 is pivoted at the point 19 to the link 9. The link 20 is pivoted at the point 21 to the link 22. The link 20 is pivoted at the point 24 to the link 25 18. The link 22 is pivoted at the point 23 to the link 16. Common with the pivot point 15 of links 11 and 16, is the pivot point of the cross ribs 25 adjustably positioned by the engagement of the set screw 26 with the 30 link 16. (See Figs. 2, 10 and 11.) Similarly at the point 24 of the link 18, is pivoted the cross rib 27, adjustably positioned by means of the set screw 28. To the forward extension 29, of the link 20, is rigidly 35 fixed the cross rib 30. This cross rib 30 is also rigidly connected to an extension of a link on the opposite side of the vehicle, similar to the link 20. Referring to the front end of the top frame, there is shown 40 fixed a bracket 31, to which is pivoted an extension 32, having a socket in the end thereof, fitting the arrow-head end of the holding rod 33. The rod 33 is clamped with the extension 32, by the hand screw 34. The 45 rod 33 is connected with the wind-shield 35 by means of the clamps 36 and 37.

Referring to the internal construction of the arms 4, 4, beginning at the stub shaft 3, of each arm, there is fixed thereto, a short 50 post-bracket 41, projecting at an angle thereto, positioned within the housing 42. A set screw 43 fixes the post-bracket 41 to the stub shaft 3. The post-bracket 41 remains in a fixed position with respect to the 55 body 1. To the post-bracket 41 is attached the flexible metal band 44, which passes over a roller 45 on the post-bracket 41.

The metal band 44, passes over the round piece 45, and around the hub of the toothed 60 wheel 46, journaled in the post-bracket 41. The metal band 44, is attached to the hub of the wheel 46. A screw 47, is positioned on post-bracket 41, to engage the teeth of the wheel 46, to hold the same from turning 65 in the square recess 48. The wheel 46 is

adapted to engage a key for turning the same. In adjusting the tension on the band 44, the screw 47 is removed to allow the wheel 46 to be freely turned and repositioned to fix the said wheel in an adjusted 70 position. The band 44, passes around a roller 49, pivoted within the housing 42, of the arm 4, and passes up from the point 44^a in cable form through a spring 50, and is connected with a washer 51, on the upper 75 end of the spring 50. The spring 50, is seated on an inturned flange 52, in the lower end of the tubular portion 53, of the arm 4. The washer 51, has a hole through which passes a cable 54.

Now tracing the course of the parts forming the cross-transmission device, starting with the cable 54 in the rear of the arm 4, passing down through the spring 50, the cable 54 connects below with the sprocket 85 chain 55, which chain engages the sprocket wheel 56, and passes up through the tubular portion 57, of the arm 4, and is fixed to the sliding bracket 58, within the ear link 14. The bracket 58, is limited in its reciprocal 90 movements by the pin 59, fixed transversely in the ear link 14. To the upper end of the bracket 58 is attached the spring 60, fixed also to the thimble 61, which is made integral with the ear link 14. Passing through 95 the upper part of the thimble 61 is an eye bolt 62, adjustably fixed thereto by the nuts 63 and 64. In the eye 65, of the bolt 62, is fixed the cable 66, which passes up through the portion 57, of the arm 4, over rollers 100 67, 67, journaled in the cross rib 5. The cable 66 continues through a channel 68, in the cross rib 5, over to the opposite end of the cross rib 5, to engage rollers 69, on the rear side of the cross rib 5, thence down 105 through a tubular portion 53, in one of the main arms 4, passing through a spring similar to 50 in the first mentioned arm 4, connecting with a chain similar to the chain 55, in the arm 4, which chain passes up through 110 a portion of the arm similar to the portion 57 of the arm 4, connecting with a link similar to ear 14, continuing on with a cable similar to 66, connected with an eye bolt similar to 62, passes up over rollers 70, in 115 the arm 5, through a channel 68, and diagonally across said cross rib 5, engaging rollers 73, 73, journaled in the curved portion of the cross rib 5. This cable next passes down through the tubular portion 53, of the arm 4, as cable 66, and connects with the sprocket chain 55, completing the continuous formation of the cable cross-transmission. In each of the sprocket wheels 56^a, there is a polygonal socket adapted to be engaged by a crank 120 for turning said sprocket wheels.

On opposite sides of the rear of the body 1, are fixed resting brackets 74—74, in which the top frame is releasably anchored in its down position.

In Fig. 4, the band 44, is shown attached to the upper end of the spring 50, holding the spring 50 in compression. In Fig. 5, a band 44^b, similar to the band 44, is shown attached to the lower end of the spring 50^a, which is anchored at its upper end to the pin 75, in the arm 4^a, holding the spring 50^a in tension. A further modification of the internal construction of the arm 4, is shown in 10 the arm 4^b.

In Fig. 6, the spring 50^b, is held at its upper end against the stop 76, and its lower end engages a washer 77, which forms a bearing plate for the convex expanded end 15 of the strut 78, adapted to rock on said washer 77. This strut 78 is pivotally connected with the post-bracket 41^b.

Considering the operation of the top frame, referring to Fig. 1, the parts thereof 20 are shown in dotted position at 79, anchored down in the bracket 74. The full line position of the arm 4, and the links attached thereto, shows the position which the parts assume when released from the bracket 74, 25 and easily pushed up by hand, the weight of the parts being overcome by means of the springs shown in one of the Figs. 4, 5 and 6, whichever construction is used.

Considering the action of the spring 50, in 30 balancing the weight upon and including the arm 4, referring to Fig. 4, the upright position of the arm 4 is shown. The arm 4, being journaled upon the fixed stub shaft 3, causes an increase in distance between the 35 roller 49 and the member 45, on the post-bracket 41, compressing the spring 50, by pulling upon the washer 51, to which the band 44, is attached. The spring being thus compressed as the arm 4 attains the 40 down position, there is a tendency to draw the roller 49, and the member 45 together, to raise the arm to its upright position, and overcome the weight thereof. The amount of compression required in the spring 50, 45 for overcoming the weight of the arm 4, and the parts attached thereto, is adjustably fixed by turning the wheel 46, after releasing the screw 47, and thereafter fixing the position of the wheel 46, by replacing the screw 47.

50 In Fig. 5, an adjustable take-up is not shown in connection with the post-bracket 41^a for the band 44^b, which is attached direct to the end of the post-bracket 41^a. The band 44^b passes around the roller 49^a 55 and is attached to the lower end of the spring 50^a.

The action of the parts within the arm 4^b, shown in Fig. 6, is illustrated in the dotted down position of the parts wherein the 60 spring 50^b is shown additionally compressed by having been forced inward, by the strut 78, during the downward movement of the arm 4^b to the dotted position. The strut 78 being pivoted to the fixed post-bracket 41^b 65 and the shaft 3 being the center of oscillation

of the arm 4^b, the strut necessarily finds play for its movement within the arm 4^b by compressing the spring 50^b, and causing a lifting movement.

Referring now to the extended dotted position of the links of the lazy-tongs, as shown in Fig. 1, a counter-clockwise turning of the lower sprocket wheel 56 (see also Fig. 4) by a suitable crank, will cause the cable 66 to raise the ear link 14, lifting the lower end 75 of the link 11, which in turn pushes up the link 9, turning the same to extend the lazy-tongs to the dotted position thereof as shown, and a continued movement will cause the links to assume the full line position of 80 the parts, as shown in Fig. 1.

Considering the operation of the cross cable transmission, as the ear link 59, passes up, the cable 71, moves up and crossing over the top of the cross rib 5, over rollers 70, 85 passes down on the rear side of the arm 41, through the balancing spring similar to 50 of Fig. 4, connects with the chain similar to 55, passing around a sprocket similar to 56, and up to an ear link similar to 59. The 90 line extends on upward over roller 68, and returns diagonally across the cross rib 5, and the channel 69, over rollers 70.

Referring to the adjustable feature for 95 taking up the slack in the cable for the cross transmission, in Fig. 8, the spring 61, always in tension, is adapted to take up some of the slack that might occur in this transmission device, but the turn-buckle 63, can be 100 adjustably fixed in the thimble 62, by means of the nuts 64 and 65, to tighten the cable 67.

Considering the development of the fan-like relative positions of the center lines of the links of the lazy tongs when brought 105 together, the diagrammatic illustration in Fig. 13, wherein the vertical line 14^b, represents the path of the pivot point 14^c, of the link 11, the center line of which is represented by the bent line 11^b. The center line 110 of the link 9, is represented by the bent line 9^b, the point 10^b representing the pivot point of the link 9, on the arm 4. Some point A, on the line 14^b, is selected as a center, from which radiate the lines B, C, D and E, 115 angularly spaced about equal. On the line B, is the pivot point F, of the line 9^b, corresponding to the link 9. Other pivot points G and H, positioned on the respective lines C and D, equidistant with the point F, 120 from the center A, determine the position of similar pivot points in the lazy tong frame. On the arc 1, are equally spaced pivot points J, K, L and M, corresponding to the pivot points at the respective crossings of the various links. On the arc N, 125 are equally spaced the pivot points O, P and Q, on the respective lines B, C and D. It is readily seen by this arrangement that the spacing between the consecutive pivot points 130

O, P and Q, is greater than the spacing between the consecutive pivot points F, G and H, due to the radial nature of the lines B, C and D, with respect to the center A. As 5 the point 14^c, is moved up on the line 14^b, to the position 14^d, the lines indicating the center line of the links will take the respective positions 9^c, 11^c, 16^c, 18^c, 20^c, 22^c, 20^d and 22^d, (the extra lines 20^d and 22^d 10 showing an extension of the system beyond that required for the number of links shown in Figs. 1 and 2) whereby as the point 13^c, moves up on the line 14^b, the pivot points O, P and Q, and the point R, will increase 15 their relative distance apart, and be on the arcs of circles of greater and greater diameter, until the arc S, is reached. Where the points F, G and H, consecutively spaced equal to the spacing of the points O, P and 20 Q, in such an extension the arc S, would be a straight line, but by conforming to some such radial arrangement all lines similar to B, C and D, pass through pivot points in the lazy tong construction. We thus systematically arrange the fanning out of the 25 upper parts of the links, and provide spaces for receiving the folded covering of the top frame.

By having the rear part of the top frame 30 fully up and the lazy tong part folded, as shown in Fig. 1, with this form of construction, one has the Victoria style of top.

In cases where the upper part of the wind-shield is curved and not adapted to 35 radially receive the end of the extended top frame, the rods 34, are provided, and may be clamped permanently at 37 and 38, leaving the frame releasably attached by means of the part 33, and the screw 35; or if de- 40 sired, the rod 34, may remain fixed in the part 33, and be releasably attached at the clamps 37 and 38, and carried back with the frame when the same is bolted.

For adjustably taking up the slack coming 45 from the stretching of the covering, the cross ribs 25 and 28, to which said covering is attached, are angularly adjusted, with respect to the respective points 15 and 24, through the agency of the adjustable screws 50 26 and 28, respectively.

Modifications of my invention other than shown in the one embodiment herein illustrated, may be made in the construction without departing from the spirit and scope 55 of said invention. I, therefore, do not wish to be confined to the one form shown herein.

Hence I claim:

1. In a top frame adapted to be attached 60 to the body of a vehicle, a bracket fixed on one side of said body, a stub shaft made integral with said bracket and extending transverse to the plane of the side of said body, a short post-bracket extending at right angles from the end of said stub shaft and made integral therewith, a swinging

arm journaled upon said stub shaft and having a cylindrical chamber open toward the journaled end of said arm, a compression spring positioned in said chamber and having its swinging end fixed to said arm, strut 70 means connecting the lower free end of said spring with the outer end of said post-bracket, whereby a swinging movement of said arm causes said spring to press upon said strut to counter-balance the weight of 75 said arm when swung back.

2. In a top frame adapted to be attached to the body of a vehicle, a pair of brackets mounted on either side of said body, a main arm connected to each of said brackets and 80 adapted to swing thereon, a cross rib connecting the swinging ends of said arms, a wheel journaled in each arm, means for turning one of said wheels, and a continuous cable-like line engaging said wheels, and 85 mounted for movement on said arms, to be moved by one of said wheels, said line being crossed on itself between said wheels, and an extensible frame pivoted to each of said arms and to said line in each of said arms, 90 for simultaneous movements in one direction with respect to said arms.

3. In a top frame adapted to be attached to the body of a vehicle, a member pivoted on said body to swing thereon, an extensible 95 set of lazy-tong links having one link thereof pivoted to said member, a sliding element 100 engaging said member, for reciprocation thereon, and having another of said links pivoted therewith, adapted to operate said links, three sets of joints connecting said links, comprising an upper, a lower and an intermediate set, the joints in said upper set being spaced farther apart than the joints in either of the two other sets, whereby 105 spaces are formed between the upper parts of pairs of links when said links are closed together, said links being formed so as to have spaces between the upper parts of pairs of connected links when said links are closed 110 together.

4. In a top frame adapted to be attached to the body of the vehicle, a bracket mounted on said body, a shaft fixed on said bracket, a post-bracket fixed on said shaft, a main arm journaled on said shaft, a spring fixed to said main arm and adapted to have its free end reciprocate longitudinally thereon, a strut member engaging the free end of said spring and said post-bracket, adapted to compress 115 said spring when said arm is moved angularly, an extensible set of lazy-tong links pivoted to said arm, a pair of wheels journaled on said arm, means for turning said wheels, and a continuous cable-like line 120 engaging one of said wheels, to be moved thereby, and mounted for movement on said arm and means for turning said last mentioned wheel, said links being connected 125 with said line.

5. In a top frame for vehicles, adapted for attachment to a vehicle body, mountings, fixed on said body on each side thereof, a stub shaft fixed in each of said mountings, a pair of arms journaled on said stub shafts, a post-bracket within each of said arms fixed to the outer end of each of said stub shafts, spring pressed means connected with the end of each of said post-brackets and 10 adapted to balance said arms in a horizontal

position and a set of lazy tongs connected with each of said arms, adapted to support a covering thereon, substantially as set forth.

Buffalo, N. Y., January 11, 1917.

EDWARD L. KUNZ.
